UNITED STATES PATENT OFFICE.

GEORGE W. NEWMAN, OF CHICAGO, ILLINOIS, ASSIGNOR, BY MESNE ASSIGNMENTS, TO KALAMAZOO LOOSE LEAF BINDER COMPANY, A CORPORATION OF MICHIGAN.

PERMANENT TRANSFER BINDER.

Application filed October 27, 1921. Serial No. 510,871.

To all whom it may concern:

Be it known that I, GEORGE W. NEWMAN, a citizen of the United States, and a resident of the city of Chicago, in the county of Cook and State of Illinois, have invented certain new and useful Improvements in a Permanent Transfer Binder; and I do hereby declare that the following is a full, clear, and exact description of the same, reference being had to the accompanying drawings, and to the numerals of reference marked thereon, which form a part of this specification.

This invention relates to a transfer binder for loose leaves in which the leaves are permanently clamped against removal.

It is an object of the invention to provide friction producing means for interlockingly clamping a pair of relatively slideable smooth leaf holding posts.

It is a further object of this invention to provide a tiltable clamp for frictionally interlocking a set of leaf holding posts.

It is a further object of this invention to provide a tiltable friction producing means for a set of leaf holding posts that is automatically tilted into operative engagement with said posts during the assembling operation.

It is a further object of this invention to provide a clamping means for a set of leaf holding posts that allows free relative sliding movement of said posts until the leaves are properly compressed.

It is a further object of this invention to provide means for frictionally clamping a set of leaf holding posts by compressing the binder.

With these and other objects in view, which will become more apparent in the following description and disclosures, this invention comprises the novel features of construction and combinations hereinafter described and more particularly pointed out and defined in the appended claims.

In the drawings, which illustrate a preferred embodiment of my invention and in which similar reference numerals refer to similar features in the different views:

Figure 1 is a perspective view of a binder containing the construction involving my invention.

Figure 2 is a section on the line 2—2 of Figure 1.

Figure 3 is an enlarged plan view of the 55 interlocking means for a set of leaf holding posts shown in section.

Figure 4 is an elevational view of a set of leaf holding posts with the interlocking means in section and in inoperative position. 60

Figure 5 is a view similar to Figure 4 with the interlocking means in operative position.

In referring now to the drawing, it will be noted that I have illustrated in Figure 1, a pair of covers 1 of suitable material and construction, having suitable hinge joints. Loose leaves are adapted to be permanently clamped between these covers by my novel mechanism. 70

In the illustrated embodiment of my invention, two sets of leaf holding posts are used. The individual posts of each set may consist of smooth flat members 2 and 3 which can be readily stamped from sheet metal or the like and provided with proper heads 4. I preferably make one of the members such as the member 2 of slightly greater width than the member 3 and curve its impaling end slightly outwardly with respect to the other member. These features aid greatly in assembling the binder. 80

Each set of posts is so supported by the covers that the individual members of each set are brought into substantial slideable 85 abutting relation when the binder is assembled, and in order to permanently clamp each set of posts when a stack of leaves has been properly compressed between said covers, a clamping member 5 has been provided 90 for each set. Each clamping member preferably consists of a slightly resilient flat metal strip having a slot near its central portion. A pair of opposite walls of said slot have reversely deflected resilient tongues 95 6 and 7 struck therefrom which exercise a clamping action upon the posts 2 and 3 that are adapted to pass through the slot. It will be noted that one portion of the slot is wider than the other portion forming thereby a pair of shoulders 8 against which the binder post 2 is adapted to abut, so that a ready space will be left for the insertion of the post 3 thereafter.

The clamping members 5 are adapted to 105 be embedded at suitable depths between the leaves so that the individual leaf holding posts of each set may pass therethrough.

Thus leaves may be impaled upon the posts 2, and after a sufficient quantity has been thuswise impaled, and before the top of said posts are buried as shown in Figure 2, the 5 clamping members 5 may be slipped over the posts 2. Leaves may then be further impaled upon the posts 2 and stacked above the clamping members 5 to any desired height, which however should not extend to 10 such a height as to prevent the posts 2 from entering the slots in the clamping members for proper clamping action therein. If desirable, a sufficient stack of leaves may be separately impaled upon the posts 2 and 15 3 to form two distinct halves. The clamping members may then be slipped over the posts 2 and the other half of the impaled leaves superimposed thereon with the posts 3 entering the slots in the clamping 20 members. In either method of impaling, the clamping members 5 will have an oblique or tilting position with respect to the posts, allowing relative sliding movement of the individual posts of each set. 25 Therefore, when the covers of the binder are pressed together to compress the leaves, the posts 2 and 3 will slide relatively to each other for this purpose. However, when the leaves have become tightly compressed, the 30 pressure will have caused the tilting clamping members 5 to assume substantially horizontal positions as shown in Figure 5, or at right angles to the posts, in which positions the tongues 6 and 7 will press against 35 the sides of the posts of each set to frictionally clamp the posts of each set together. It should be noted that the tongues 6 and 7 are so directed that any force tending to expand the binder or separate the 40 covers will increase the clamping action or friction between the respective post of each set.

It will accordingly be apparent that I have devised a clamping member that cooperates 45 with the leaf holding posts in such a way that relative slidable movement of the posts is permitted for firmly compressing the leaves of the binder, and wherein a strong frictional clamping action of the posts is 50 attained when proper compression of the leaves occurs, and which frictional clamping action increases upon any tendency of expansion of the binder.

I am aware that numerous details of construction may be varied through a wide 55 range without departing from the principles of this invention, and I therefore do not purpose limiting the patent granted otherwise than necessitated by the prior art.

60 I claim as my invention:

1. In a transfer binder, a set of relatively 65 slidable and smooth posts, and a slotted member having reversely deflected resilient tongues adapted to receive said posts, said

to horizontal position by compression of the leaves of the binder for frictionally clamping said posts.

2. In a transfer binder, the combination with a pair of relatively slidable and smooth 70 impaling posts, and means tiltable by compression of the leaves of the binder for frictionally clamping said posts together.

3. In a transfer binder, a plurality of sets of relatively slidable and smooth impaling 75 posts, and slotted members having reversely deflected resilient tongues adapted for receiving said posts when said members are in tilted position, said members being pressed from tilting to horizontal position 80 by compression of the leaves of the binder for frictionally clamping each set of posts together.

4. In a transfer binder, a set of relatively 85 slidable and smooth impaling posts, and a 90 tiltable clamping member having an aperture with resilient walls for receiving said posts when in inclined position and frictionally clamping the same together when said member is tilted to horizontal position. 95

5. In a transfer binder, a set of relatively 100 slidable and smooth impaling posts adapted for securing the leaves of the binder, and a clamping member therefor having an aperture with reversely directed resilient tongues 105 for receiving said posts when in inclined position, said member being adapted to be embedded in the leaves of the binder, and straightened to horizontal position by compression of the leaves for frictionally clamping said posts together.

6. The combination in a binder for sheets 110 perforated to receive binding posts, binding bars, post members arranged on said binding bars in coacting pairs for slidable engagement within the sheet body, and a clamping means adapted to be disposed between sheets of the sheet body and actuated by the pressure of the sheets thereon to clamp the post members together.

7. The combination in a binder for sheets 115 perforated to receive binding posts, of a coacting pair of post members adapted for slidable engagement within the sheet body when introduced into said sheets from opposite sides of the body, and a clamping means disposed between sheets of the said body, and adapted to be actuated by pressing the sheets thereon to clamp the post members together.

8. The combination in a binder for sheets 120 perforated to receive binding posts, of binder bars, binding post members mounted on said bars in coacting relation for sliding engagement within a sheet body and a post clamping means adapted to be interposed between the sheets to be bound for clamping said post members together, said post clamping means being actuated by the compressing of the sheets thereon.

9. The combination in a binder for sheets perforated to receive binding posts, of a pair of post members adapted to telescope within the sheet body when introduced into said sheets from opposite sides of the body, and a post clamping member through which said post members are disposed tiltably associated therewith and adapted to be interposed between the sheets to be bound and actuated by the pressure of the sheets thereon to post clamping position. 40
10. The combination in a binder for sheets adapted to receive binding posts, of a co-acting pair of post members telescopingly associated when introduced into said sheets from opposite sides of the sheet body, and a clamping member adapted to be interposed between the sheets and tiltably associated with said posts and adapted when actuated to a position at right angles thereto by pressing the sheets thereon to clamp the post members. 50
11. The combination in a binder for sheets perforated to receive a binding post, of a pair of post members adapted to telescope within the sheet body when introduced into said sheets from opposite sides of the body, and a post clamping member adapted to be interposed between the sheets to be bound and tiltably associated with said sheets to be actuated by the pressure of the sheets thereon to post clamping position. 55
12. The combination in a binder for sheets adapted to receive binding posts, of a co-acting pair of post members telescopingly associated when introduced into said sheets from opposite sides of the sheet body, and a clamping member adapted to be interposed 60
15. The combination in a binder for sheets adapted to receive a binding post, a coacting binding post, and a clamping member adapted to be interposed between the sheets to be bound and having a hole therein through which said post is freely movable when the clamping member is disposed in an inclined position relative to the post and the sheets, said clamping member being 65
20. The combination in a binder for sheets, of a sheet binding post, and a post clamping member adapted to be interposed between the sheets to be bound and tiltably associated with said post and the sheets to be bound to be actuated by the pressure of the sheets 70
25. The combination in a binder for sheets adapted to receive a binding post, and a post clamping member associated with said sheets to be bound and tiltably associated to be swung to post clamping position by pressing the sheets thereon. 75

In testimony whereof I have hereunto subscribed my name.

GEORGE W. NEWMAN.
